UNITED STATES PATENT OFFICE.

WILLIAM S. WARD, OF LEADVILLE, COLORADO.

ORE-CONCENTRATOR.

SPECIFICATION forming part of Letters Patent No. 276,738, dated May 1, 1883.

Application filed February 26, 1883. (No model.)

To all whom it may concern:

Be it known that I, W. S. WARD, of Leadville, county of Lake, and State of Colorado, have invented certain new and useful Improvements in Ore-Concentrators, of which the following is a full, clear, and exact description, reference being had to the accompanying drawing, forming a part of this specification.

My invention relates to ore-concentrators of that kind wherein the pulp is fed from an elevation, passing through a suitable conduit, so as to force itself through the concentrator by hydrostatic pressure or by any of the usual methods of producing a forced injection; and the invention consists, first, in an ore-concentrating apparatus, the combination of a suitable vessel, an interior vessel or funnel, an inlet tube or conduit connected with the outer vessel near its bottom, and exit port or ports for drawing off the concentrations from the apparatus; second, the combination, with the vessel and funnels, of deflectors to throw the pulp toward the center of the vessel, and in further details of construction which will be particularly pointed out in the claims.

In the drawing, which is a section of an ore-concentrator made according to my invention, A represents a vessel of cylindrical or other form, made of sheet or plate iron, wood, or other suitable material. Connected with this vessel is a feed-pipe or conduit, B, the junction being shown at B''. A hopper, B'', should be attached to or supported above the conduit B. Inside the vessel I secure and support by brackets what I call a "funnel," C. The lower end of this funnel leads through the bottom of the vessel and ends in a pipe, C', from which the concentrated ore may be drawn. This pipe or nozzle may be provided with a cock or other device to regulate the flow or to cut it off altogether. The lower end of the vessel is also provided with an exit, A', as shown, similar to C', for taking off ore or for

flushing and cleaning, &c. Any number of additional funnels, as D, may be provided in addition to the primary funnel, C, so as to grade the ore and deposits according to its specific gravity. D has its exit-orifice at D', as shown. Guards or deflectors e e are placed just above the top of the funnels C D, so as to deflect both the upward and downward currents toward the center of the vessel, and thereby avoid carrying the heavy metallic portions of the pulp up and out of the overflow-openings ff.

By the introduction of the pulp at the bottom and forcing it up between the funnels and the walls of the vessel, and by having the deflectors e e, a capacity is given to an apparatus of given dimensions beyond anything known to me. Moreover, the facility of operating and of drawing off the settling or concentrations, either constantly or at intervals, largely augments the working capacity of this apparatus.

Having thus fully described my invention, what I claim as new, and desire to secure by Letters Patent, is—

1. The combination of an exterior vessel, an interior funnel, an inlet-conduit connected with the outer vessel outside and near its bottom, and an exit-port from the funnel, as specified.

2. The combination of an exterior vessel, an interior funnel, an inlet-conduit connected with the outer vessel outside and near its bottom, and exit-ports from each compartment of the apparatus.

3. The combination, in an ore-concentrator, of the vessel, funnels, and deflectors, as herein set forth.

4. The combination of the vessel, funnels, deflectors, and conduit or supply-pipe, as described.

WILLIAM S. WARD.
